John A. Solheim et al., "Golf Club with Hosel Inserts and Methods of Manufacturing Golf Clubs with Hosel Inserts," U.S. Appl. No. 13/795,653, filed Mar. 12, 2013.

Primary Examiner — Mitchell Siegel

CLAIM

The ornamental design for a golf club hosel sleeve, as shown and described.

DESCRIPTION

FIG. 1 is a top perspective view of a golf club hosel sleeve; FIG. 2 is a bottom perspective view of the golf club hosel sleeve of FIG. 1; FIG. 3 is a front elevational view of the golf club hosel sleeve of FIG. 1; FIG. 4 is a rear elevational view of the golf club hosel sleeve of FIG. 1; FIG. 5 is a top view of the golf club hosel sleeve of FIG. 1; FIG. 6 is a bottom view of the golf club hosel sleeve of FIG. 1; FIG. 7 is a left side view of the golf club hosel sleeve of FIG. 1; and, FIG. 8 is a right side view of the golf club hosel sleeve of FIG. 1.
